United States Patent Office

Des. 227,327
Patented June 19, 1973

227,327

CABINET

William H. Tucker, Columbus, and Samuel C. Von Brock,
Lancaster, Ohio, assignors to Martec Corporation,
Columbus, Ohio

Filed Apr. 26, 1971, Ser. No. 137,746

Term of patent 14 years

Int. Cl. D6—04

U.S. Cl. D6—150

Fig. 1

FIG. 1 is a view in perspective of a cabinet, embodying the invention.

FIG. 2 is a view in perspective of the embodiment of FIG. 1 with the cabinet opened to illustrate its interior.

FIG. 3 is a modified form of the cabinet of FIG. 1.

The side of the cabinet, not shown, is like the side shown while the back is conventionally plain and unornamented.

We claim:

The ornamental design for a cabinet, as shown and described.
